MAGAZINE FILLING MACHINE AND
DISPENSER MAGAZINE

Gustav Koren, New York, N. Y.

Application July 3, 1934, Serial No. 733,669

2 Claims. (Cl. 1—49.6)

The invention relates to a magazine filling machine and dispensing magazine for fastener members and more especially to a tack magazine filler and dispenser for tacks.

5 The primary object of the invention is the provision of a machine of this character, wherein tacks will be fed into a magazine for the dispensing of such tacks when the magazine is used, the said magazine being serviceable to upholsterers for the successive feeding of tacks when engaged in upholstering work, and thereby eliminating the necessity of the placing of tacks in the mouth of such artificer, which is most dangerous and unhealthy.

15 Another object of the invention is the provision of a machine of this character, wherein the construction thereof is novel in form and will operate to automatically supply tacks to a dispensing magazine which has a hand appliance for the delivery of tacks one by one for the convenience of an artificer, such as an upholsterer or other person requiring the use of tacks as fasteners, the machine being also adaptable for the feeding of other fasteners, as for example, screws, headed

20 nails or the like.

25 A still further object of the invention is the provision of a magazine of this character, wherein tacks are held in clips, these serving to dispense the tacks successively in single order, so that they

30 may be utilized in upholstery work and thus relieve an upholsterer from carrying the tacks in the hand or in the mouth, as is generally the habit of those engaged in upholstery work, the hands being free for tool handling in the execution of

35 upholstery work.

A still further object of the invention is the provision of a machine of this character, wherein the tacks introduced thereto will be sorted into groups for the filling of a dispensing magazine 40 with dispatch and such magazine will afford delivery in single order of the tacks therefrom or from the clips as contained therein, the tacks being received in single order by the fingers of an artificer, such as an upholsterer, for the utilization 45 of the tacks in upholstery work.

A still further object of the invention is the provision of a machine of this character which is comparatively simple in construction, thoroughly reliable and effective for its purpose, readily and easily operated, assuring the filling of the tack dispensing magazine with dispatch, and inexpensive to manufacture.

With these and other objects in view, the invention consists in the features of construction, combination and arrangement of parts as will

be hereinafter more fully described in detail, illustrated in the accompanying drawings, which disclose the preferred embodiment of the invention, and pointed out in the claims hereunto appended.

In the accompanying drawings:

Figure 1 is a vertical longitudinal sectional view through a machine and the dispensing magazine constructed in accordance with the invention, the magazine being joined with the machine for the filling of said magazine with tacks.

Figure 2 is a sectional view on the line 2—2 of Figure 1 looking in the direction of the arrows.

Figure 3 is a sectional view on the line 3—3 of Figure 1 looking in the direction of the arrows.

Figure 4 is a sectional view on the line 4—4 of Figure 1 looking in the direction of the arrows.

Figure 5 is a fragmentary rear elevation of the socket part for the attachment of the magazine to the machine.

Figure 6 is a fragmentary sectional view on the line 6—6 of Figure 1 looking in the direction of the arrows.

Figure 7 is a fragmentary top plan view of the tack runway or feed chute and adjuncts of the machine.

Figure 8 is a perspective view of a runway supporting bracket combined with a clapper.

Figure 9 is a sectional view on the line 9—9 of Figure 1 looking in the direction of the arrows.

Figure 10 is a transverse sectional view through a coupling head for a magazine on the line 10—10 of Figure 11 looking in the direction of the arrows.

Figure 11 is a sectional view on the line 11—11 of Figure 10.

Figure 12 is a fragmentary vertical longitudinal sectional view through the magazine showing the manner of coupling the body of the magazine with the coupling head of the machine.

Figure 13 is a vertical transverse sectional view through the coupling head.

Figure 14 is a vertical transverse sectional view through the lower end of the runway or feed chute for the tacks.

Figure 15 is a plan view of the magazine ready for service.

Figure 16 is a view similar to Figure 15 showing the end head or cap removed.

Figure 17 is a sectional view through one of the caps for the magazine.

Figure 18 is a vertical transverse sectional view through the magazine showing in detail an end head mounted thereon.

Figure 19 is a side elevation thereof.

Figure 20 is an enlarged sectional view on the

line 20—20 of Figure 19 looking in the direction of the arrows.

Figure 21 is a fragmentary perspective view of one of the tack clips in the magazine and the 5 same being partly broken away.

Figure 22 is a sectional view on the line 22—22 of Figure 19 looking in the direction of the arrows.

Figure 23 is a fragmentary perspective view of the dispensing tip for the magazine.

10 Figure 24 is a side view thereof.

Figure 25 is a perspective view of another of the adjustable dispensing tips for the magazine.

15 Similar reference characters indicate corresponding parts throughout the several views in the drawings.

Referring to the drawings in detail, the machine comprises a suitable base A, upon which is secured a U-shaped bracket 10, the arm 11 of which constitutes a coupling for an upright 12, 20 while the other arm 13 of said bracket has fixed thereto the upright 14 (Figs. 1, 2, 4), this having a circular upper end 15 formed with a seat 16. Accommodated within the seat 16 is the forward smaller end of a conical-shaped drum 17, the 25 opposite larger end 18 thereof being closed, while the smaller end is closed by the end 15 of the upright 14. The drum 17, at the end 18, has formed at intervals thereof the receiving pockets 19 for tacks 20 introduced into the drum. Each 30 pocket 19 is laterally tilted and communicates with the drum through a slot 21 (Fig. 3) which is located next to one side wall of the pocket 19, while at the other side wall of said pocket is the ledge 22, and in this fashion the tacks 20 contained 35 within the pockets will by gravity discharge into a hopper 23 formed at the uppermost end of an inclined runway or feeder trough 24 arranged interiorly of the said drum 17. This runway or trough 24 has its lowermost end loosely extended 40 through an opening 25 in the end 15 of the upright 14. The uppermost end of the runway or trough 24 has connection with a coupling 26 about a stationary center axle 27 for the said drum. The axle 27 is formed with the journal end 28 fitting the hub 29 of the end 18 of said drum 17. 45 The hub 29 is formed with a handle-engaging stub 30 to which is detachably secured a crank handle 31. Thus it will be seen that by rotating the handle 31 the drum 17 will likewise be rotated, 50 so that the tacks 20 as gathered at the lowermost portion of the drum 17, on rotation of the latter, will gravitate into the pockets 19 and when these pockets successively reach the highest path of motion of the drum 17, the said tacks will drop into 55 the hopper 23 to be received within the runway or chute 24 with their shanks engaged in said runway or chute and the heads of the tacks gliding upon the runway or chute for a purpose presently described.

60 The coupling 26 carries a clapper 32 which when operating has a hammering action against one side of the runway or chute 24 for vibrating the same, so that the tacks 20 therein will be caused to gravitate along the runway or chute, the clapper 32 being actuated by tripping bobs 33 on the end 18 and in the path of the free end of said clapper. These bobs 33 in the rotation of the drum engage the free end of the clapper 32 at its striking side so that this end rides over the bobs in the direction 65 of the chute for striking action.

70 The end 15 of the upright 14 (Fig. 1) carries a filling spout 34, so that tacks dumped therein will be delivered into the drum 17, there being a deflector guard 35 overhanging the runway or chute 24 at the filling spout 34, so that tacks entering

the drum will be deflected away from the runway or chute 24 to fall within the said drum.

Overhanging the runway 24 and carried by the end 15 is a guard 36 which functions to knock away those tacks 20 improperly righted or irregularly coasting upon the runway or chute 24 so as to eliminate the jamming of the said runway or chute at the clearance point 37 for the heads of said tacks when gliding within the runway or chute for their feed into a tack magazine hereinafter 10 described.

The axle 27 for the drum 17 is made from a tube longitudinally split for a considerable length thereof to form the forwardly divergent portions 38, these being made fast to the ends 15 of the 15 uprights 14 and thus assuring rigidity and brace to the said axle.

20 Mounted on the upright 14 is an angularly disposed coupling head 39 in the form of a rimmed cap which has the lowermost end of the runway or chute 24 extended therein and this cap is formed with an annular rim 40 transversely split and cut from said cap for a distance removed from the said split to provide the spring clips or tongues 41, these with the rim 40 being 25 provided with a bead 42 for latching engagement and rotatable coupling of a magazine shell or body 43 with said head 39. The shell or body 43 (Fig. 9) of the magazine has radially arranged 30 therein a series of tack receiving clips 44, these being made fast within said body and adapted for individual or single alignment with the runway or chute 24 when the shell or body 43 is coupled with the head 39 and in successive order, 35 so that the tacks riding the runway or chute 24 will fill the clips 44 for carriage within the said magazine to permit dispensing of the tacks therefrom in a manner presently described. The clips 44 are singly brought into confronting relation to the runway or chute 24 when the shell or body 40 43 is attached to the head 39 by rotating the said shell or body 43 in the head 39. The opposite end of the shell or body 43 has provided externally 45 thereof the ratchet formations 45 (Fig. 16) for coaction with a ratchet dog 46 (Fig. 10 and 11) 45 carried by the head 39 and thus the shell or body 43 can be rotated in the head 39 in but one direction. These ratchet formations 45 at the opposite end of the shell or body 43 are calibrated 50 correspondingly to the location of the clips 44 as contained within said shell or body, so that by the ratchet action it can be determined when a single clip 44 is in alignment with the runway or chute 24 for the reception of the tacks 20 within said clips, the clips being successively 55 brought into confronting relation with the runway or chute 24 on rotating the shell or body 43 of the magazine in one direction.

The lower portion of the runway or chute 24 has one side wall 46' fixed and the other side 60 wall 47 free, so that this side wall 47 free will vibrate under the influence of the clapper 32 as the drum is turned from left to right (see Figure 6) to assure the successful feeding of the tacks 20 into the clips 44 for the filling of the magazine, 65 as should be clearly obvious.

Beneath the lower end portion of the runway or chute 24 between the upright 14 and the head 39 is a relief trough 48 for receiving the tacks 20 that may become crowded at the lower end of the 70 runway or chute 24 resultant from a complete filling of a clip 44 and those tacks liberated into the relief trough 48 will gravitate into a catcher 49, which in its construction is similar to the head 39 except that it is releasably held within 75

a holding yoke 50 upon the base A for service in a manner presently described. The tacks 20 as collected within the head 49 can be replaced in the drum 17 by the dumping thereof into the spout 34.

Surrounding the hub 29 for the axle journal 28 is a coiled tensioning spring 51 which urges the drum 17 in a direction to have the smaller end thereof maintained in the seat 16 in the end 15 of the upright 14 at all times.

The body or shell 43 of the magazine carries a dispensing head 52 (Figs. 1, 15 and 19) provided with a tack dispensing stationary tip 53, having spring lips 54 and 55, respectively, and upon this 15 tip is fitted an adjustable dispensing tip 56 (Figs. 19 and 25) having the spring lips 57 and 58, respectively, the tip 56 being adjustable by a knurled nut 59 on a threaded pin 60 made fast in the head 52, and through these tips 53 and 56 20 are hand extracted singly the tacks 20 from the clips 44 successively on the same being brought into confronting relation to said stationary tip 53. The adjustable tip 56 is provided to take care of wear upon the stationary tip 53 and its 25 self under the extraction activity in the use of the magazine. The tacks 20 (Fig. 19) are extracted from the tips 53 and 56 one by one by the hand of the user of the magazine. The head 61 of each tack when at the extraction end of 30 the tip 56 is sufficiently exposed therefrom for the ready gripping of the tack by the fingers of the hand and on a slight pull upon the tack the same is extracted from between the tips 57 and 58 of said tip 56. This tip 56 is cut away, at 62, 35 between the lips 57 and 58 for the exposure of the periphery of the head 61 of said tack when passing into the said tip, so that it can be manually gripped by the fingers of a person to extract the tack from between the spring lips 58 40 beneath the lip 57. The lips 54, 55, 57 and 58 are of thin springy metal and should these become worn or spread the same can be bent into shape for proper service thereof to avoid the accidental dropping of the tacks from the tips.

45 The end head 52 (Figure 18) is substantially similar to the head 39 except that it carries internally thereof a split spring ring 63 which functions to rotatably secure the said head 52 upon the outermost ratchet end 45 of the body 43 and 50 ratchet action had by the part 46a.

When the body 43 of the magazine is detached from the head 39 permanently carried by the machine, after the filling of the clips 41 within said body, a separable cap 64 is applied to the body. 55 This cap 64 is similar to the head 39 and has swiveled centrally thereof an eye 65 through which is trained a suitable suspension strap 66 to be placed about the neck of a person for the hanging of the magazine on the person, so that 60 it will be serviceable for the dispensing of tacks when carrying forth upholstery work or other work requiring the use of tacks.

When it is desired to store the magazine, or to transport it, there is provided a head 49 (Fig. 2) 65 held in a holder 50 which may be substituted for the head 52. By this substitution the magazine 43 will be closed and prevent the displacement of the tacks carried by the clips 41.

It should be apparent that the drum 17 can be 70 filled with loose tacks 20 by deposit therein from the spout 34, these tacks being poured into said spout, and on manual rotation of the drum the loose tacks will fall within the respective pockets 19, whence during rotation of the said drum the tacks within the pockets will be caused to drop

5 into the hopper 23 which delivers the tacks into the chute 24 and under vibratory action these tacks within the chute will gravitate into the clips 41 within the body 43 of the magazine for the filling thereof.

When the magazine has been completely filled by the storage of tacks within the clips 41 in its body, the said magazine is then conditioned for carriage upon the person through the medium of the strap 66 and a clip 67 which engages the body 10 15 garment of the person, this clip being upon the head 52 and by rotating the body 43, it being understood, of course, that the head 52 is maintained stationary, the various clips 41 of the series as filled with tacks can be brought into position to deliver singly the tacks therefrom into the tips 53 and 56, whence the user of the magazine can extract these tacks in their single order by grasping the heads 61 of the tacks 20 and pulling the same from between the lips 58 of the 20 adjustable tip 56 for their consumption. Wear from extracting tacks takes place from the extreme lip 54 and at its inner face, thus failing in holding the head of the tack so to relieve this condition there has been provided the adjustable 25 tip 56 having the lips 57 and 58, respectively, serving as an auxiliary to the tip 53.

It also should be obvious that in event of the tacks 20 dropping from the pockets into the trough 23 and not becoming righted, the guard 36 30 will disperse those tacks so that they will drop within the drum 17 to be subsequently picked up by the pockets 19 and delivered into the runway or chute 24 therefor for the filling of the magazine, as hereinbefore stated.

35 The uprights 12 and 14 are detachably secured by fasteners 69 and 70, respectively, to the limbs or arms of the bracket 10. The crank handle 31 is detachable from the threaded stem 30 of the hub 29.

40 By the use of the machine the clips 41 in the body 43 of the magazine can be filled with tacks with considerable rapidity and the said tacks filling the magazine can be readily dispensed therefrom by finger engagement therewith in 45 single order without inconvenience to the user of the magazine.

What is claimed is:

1. A machine of the character described comprising a substantially conical shaped drum having 50 pockets circumferentially arranged next to the larger end thereof, means rotatably supporting the said drum, a feed trough arranged interiorly of the drum and inclined in the direction of its smaller end with the lowermost end of said 55 trough projected exteriorly of the drum, a hopper at the uppermost end of said trough for delivering tacks to the latter from the said pockets, a clapper operating upon the trough for vibrating the same to effect the gravitation of the tacks 60 therein, means on the drum for intermittently operating the clapper, a magazine coupling head associated with the supporting means for the drum and having the feed trough extended there-through for communication with the magazine 65 when fitted with said head, a feed spout associated with said supporting means and inclined toward the larger end of the drum and extending through the smaller end of the latter above the 70 feed trough, a guard associated with the trough for knocking tacks therefrom when irregularly coasting upon said trough to eliminate jamming thereof, and a relief trough carried by the supporting means for the drum for receiving tacks 75

that may become crowded at the lower end of the trough.

2. A machine of the character described comprising a substantially conical shaped drum having pockets circumferentially arranged next to the larger end thereof, means rotatably supporting the said drum, a feed trough arranged interiorly of the drum and inclined in the direction of its smaller end with the lowermost end of said trough projected exteriorly of the drum, a hopper at the uppermost end of said trough for delivering tacks to the latter from the said pockets, a clapper operating upon the trough for vibrating the same to effect the gravitation of the tacks therein, means on the drum for intermittently operating the clapper, a magazine coupling head associated with the supporting means for the

drum and having the feed trough extended therethrough for communication with the magazine when fitted with said head, a feed spout associated with said supporting means and inclined toward the larger end of the drum and extending through the smaller end of the latter above the feed trough, a guard associated with the trough for knocking tacks therefrom when irregularly coasting upon said trough to eliminate jamming thereof, a relief trough carried by the supporting means for the drum for receiving tacks that may become crowded at the lower end of the trough, and a catcher associated with the relief trough for receiving tacks therefrom liberated thereto from the trough. 5 10 15

GUSTAV KOREN. 15
